UNITED STATES PATENT OFFICE.

EZRA S. AVERY AND ORA O. FUSCH, OF SAN JOSE, CALIFORNIA.

ELECTRIC FLATIRON.

Application filed July 22, 1920. Serial No. 398,196.

To all whom it may concern:

Be it known that we, EZRA S. AVERY and ORA O. FUSCH, citizens of the United States, and residents of San Jose, in the county of 5 Santa Clara and State of California, have invented certain new and useful Improvements in Electric Flatirons, of which the following is a specification.

Our invention relates particularly to a 10 means for controlling the flow of electricity through an electrically heated flat iron. It is the object of our invention to provide a means conveniently incorporated in the structure of the flat iron whereby a rise of 15 temperature above a given point will automatically break the flow of electricity to the iron, and a corresponding drop in temperature will automatically close the circuit again. Also to provide suitable means of the 20 character indicated which can be quickly and easily set to break the current at varying temperatures as desired or to break the current completely without the use of an additional switch and without disconnecting the 25 iron from the supply connection. Still another object of our invention is to provide an iron of the character indicated which is provided with an electric light element inserted in the wiring system thereof and arranged to 30 be visible to the operator of the iron thereby indicating instantly the breaking of the circuit from any cause whatever.

Other objects and advantages will appear in the following description and in the 35 drawing, in which:—

Figure 1 is a plan view of an iron embodying our invention, the handle thereof being removed.

Figure 2 is a sectional view on line 2—2 of 40 Figure 1.

Referring more particularly to the drawing, 1 indicates the body portion of an electric flat iron having a suitable heating element inserted therein at 2, connected to one 45 plug terminal 3 by wire 4, the other plug terminal being shown at 5 and a portion of the handle at 6 mounted on top portion 7 by screws 8.

On body portion 1 and beneath top 7 and 50 one on each side of handle portion 6 are two posts 9 and 10 held in position by screws 11 and 12, the latter also binding to said posts the two ends of expansion member 13 having a contact boss formed on its central portion 55 as at 14.

Mounted in vertical alignment with the axis of boss 14 is a screw provided with a contact point 16, both of electricity conducting material, the screw 15 being threaded into a bearing 17 mounted on handle portion 6 and extending downwardly through top 7 as shown. The upper end of screw 15 is provided with a head 18 to which is attached a pointer 19 set to operate in conjunction with suitable indicia as "off" "warm" "hot" 65 shown at 20, 21 and 22 respectively. The binding post 15—17—18 is connected by a wire 23 to the opposite end of the heating element 2 than that to which terminal 3 is connected.

Mounted on body 1 and within top 7 is a small electric bulb 24 visible from the outside through a window 25 in said top 7 and connected to post 10—12 by wire 26 and to terminal 5 by wire 27.

From the above description it is clear that when a plug suitably connected to a source of supply is inserted on terminals 3 and 5 the current will flow through the following elements:—3—4—2—23—15—16—14—13—80 26—24—27—5, thereby heating the iron and lighting bulb 24. The parts 15—16—14 and 13 are so arranged that 14 and 16 are in contact when pointer 19 indicates "warm" or "hot". If however, the pointer indicates 85 "warm" and the iron itself becomes sufficiently warm to expand strip 13, then the same expands and draws boss 14 away from point 16 and the circuit is broken and remains broken until the temperature drops 90 and permits strip 13 to contract sufficiently for boss 14 to again contact with point 15. If the pointer indicates "hot" then the same operation occurs but the point 16 being advanced a little a higher temperature is required to separate boss 14 from point 16. If the pointer indicates "off" then the threaded member 15 has so far withdrawn point 16 that contact with boss 14 is broken and no current flows.

It is to be understood of course that changes in form, construction, and details of operation may be made within the scope of the appended claims;—

We claim:—

1. In combination with an electric heater of the character described a current conducting element connected in series with the electric circuit of the heater and having a known coefficient of expansion, means asso- 110

ciated with said element by which a predetermined amount of current is permitted to flow through said electric heater, and means visually indicating the degree of heat the 5 electric heater will attain before the circuit is broken.

2. In combination with an electric heater, a current conducting element connected in series with the circuit of the electric heater 10 and having a known coefficient of expansion, means for suspending said element so that the same may sag when expanding, contact and connecting means by which the circuit of the electric heater will be opened when 15 said element has sagged a predetermined degree, and visual means for indicating the degree of heat the electric heater will attain before its circuit is broken.

3. In combination with an electric heater 20 of the character described, an electric conducting element having a known coefficient of expansion connected in series with the electric circuit of said heater, means for suspending said element so that it may sag 25 when expanding, a screw mounted above the point of sagging of said element and normally in engagement therewith, connecting means for placing said screw in series with said element whereby when said element sags 30 a predetermined degree the circuit of the electric heater will be opened, and a pointer extending from said screw and a dial there-

for, by which the approximate degree of heat permitted for the electric heater may be indicated.

4. In combination with an electric heater, a thermostatic element, means for suspending said element so that the same may sag with the heating thereof, means whereby upon the sagging of the thermostatic element a predetermined degree the electric circuit of said heater will be opened, and means for visually indicating the degree of heat the heater will attain before its circuit is broken. 40

5. In combination with an electric heater, 45 a thermostatic element, means for suspending said element so that the same may sag with the heating thereof, means whereby upon the sagging of the thermostatic element a predetermined degree the electric circuit of said heater will be opened, a contact point adjustable relative to the sagging portion of said thermostatic element and adapted to establish a circuit therewith, means whereby upon the thermostatic element sagging a sufficient degree to become disconnected from the contact point the electric circuit of the heater will be opened, and means actuated by the adjustable contact point adapted to visually indicate the degree 50 of heat the electric heater will attain before its circuit is broken. 55
